ACOUSTICAL APPARATUS

Allan W. Fisher, St. Petersburg, Fla.

Application December 11, 1937, Serial No. 179,373

8 Claims. (Cl. 181—31)

This invention relates to acoustical apparatus and more particularly to a loud speaker for use in connection with sound reproduction.

Acoustical devices for the reproduction of sound and loud speakers in use today fail to present proper tonal effects in that essential resonating features have not been incorporated in their design. Previous to my invention, manufacturers have been reluctant to provide proper resonating means, baffles, sounding board, and flare members because of lack of space in a cabinet of reasonable size with known arrangements of parts.

Some manufacturers of radio sets today are so designing their speakers in relation to the remainder of the apparatus that when sound emanates therefrom more or less objectionable resonance tones accompany the sound reproduction.

It is an object of my invention to provide a loud speaker having pleasing tonal qualities and resonating features of compact form.

It is a further object of the invention to provide sound reproducing apparatus with an arrangement whereby resonance emanating therefrom may be controlled by the listener or operator.

Other objects and the nature and advantages of the invention will be apparent from the following description taken in conjunction with the accompanying drawing, wherein:

Fig. 1 is a front elevation of sound reproducing apparatus with parts cut away disclosing a loud speaker in accordance with the invention;

Fig. 2 is a section taken along line 2—2 of Fig. 1; and,

Fig. 3 is a fragmentary section taken along line 3—3 of Fig. 2 looking in the direction of the arrows disclosing the mechanism for controlling resonance.

Referring to the drawing, cabinet 10 is arranged to house a sound reproducing apparatus in the upper portion thereof which may take the form of a radio set 11 having a volume control and switch knob 12, a tuning control knob 13, tuning dial 14, and resonance control knob 15. In the lower portion of the cabinet an inclined sounding board 16 may be arranged having secured thereto by any suitable means a conventional loud speaker 17. A flare member 18 which may take the form of a hollow frustrated cone is secured to the rear portion of the sounding board and the outlet of the speaker. The sounding board 16 has arranged thereon and therethrough a desired number of resonating tubes 19, I have shown twelve in Fig. 3, for attributing to the device

proper pleasing tonal effects. The tubes 19 are arranged on the sounding board 16 in a manner such that their axes are perpendicular to the sounding board and in line with the loud speaker 17, the axis of which is also perpendicular to the sounding board and further in a manner such that the front faces 20 of the tubes 19 lie in a plane parallel to the front of the cabinet and intersect said plane to form ellipses as shown in Fig. 1. To effect this arrangement the shorter tubes are placed near the bottom of the sounding board 16 which is inclined in a manner whereby its bottom portion is relatively close to the front of the cabinet, its top portion is relatively far from the front of the cabinet, and the succeeding longer tubes are arranged higher up on the sounding board 16 as shown on the drawing. In addition to the tubes 19 that transmit the tone from the front of the speaker, another set of tubes 21 may be arranged in circular form about the tubes 19 and through the sounding board 16 in communication with the space between flare member 18 and housing 22 which envelops speaker 17 but is arranged in spaced relation thereto and secured to sounding board 16 in a manner to include the portions of the tubes 21 arranged in the sounding board whereby the tubes 21 may carry sound that originates from the rear of the speaker, which involves more or less objectionable resonance tones, and is sometimes desirable and at other times undesirable. The housing 22 may be fabricated of sound deadening material such as felt paper, for example.

In practice I have found that the sound that emanates from the speaker is weaker at or near its circumference and to compensate for this weakness tubes 21 have been provided to bring additional volume from the rear of the speaker which more or less equalizes the sound emanating from substantially the entire area of the sounding board. Should this added sound be too great for the room or listener, I may provide a control, comprising knob 15 cooperatively associated with shaft 23 in a manner whereby through worm and gear mechanism 24, the shaft 25 may rotate pulley 26 winding thereon wire 27 which is attached to rotate at annular disc 28, at ear 29, causing said annular disc to rotate in the direction of the arrow as shown in Fig. 3. Tending to pull rotating annular disc back to its original position is spring 30 fixed to a portion of the cabinet by hook 31 at one end and at its other end fastened to wire 32 which engages ear 33 of the rotating disc 28. Guide means 34 may be provided in cooperative relation to rotating disc 28 whereby

circular openings 35 arranged in said annular disc to correspond with the openings in tubes 21 may transmit all, part or substantially prevent the transmission of sound from the rear of the speaker, through tubes 21 to the listener, depending on the position of the annular disc 28 which in turn is controlled by the knob 15.

On the front of the sounding board completely housing the resonating tubes 19 and the tubes 21 a housing 36 may be provided with a substantially circular cross section at its base 37, and an inwardly curved portion at its front end 38. The housing 36 may be fabricated of a sound deadening material such as paper or the like. With this arrangement sound emanating from the resonating tubes will be concentrated and prevented from spreading over a wide area thereby giving warmth to the sound reproduction which is noticeably pleasant. The housing 36 is similar in design to the shape formed by a singer's lips to concentrate the sound emanating from his mouth and which gives a mellow effect thereto.

With the arrangement described, sound may be reproduced in a pleasing and effective manner with the absence of harsh vibrant effects, with a control of resonance and in a greater volume without distortion. Frequently, a listener to or operator of a radio set, as manufactured today, will be unable to satisfactorily hear the tones of the various instruments of the original composition unless the volume control is turned up to a point where it is no longer pleasing, because of the accompanying excess noise or volume. With my invention, however, it is possible to reduce the size of the speaker proper and still receive the desired tonal effects which makes it feasible to produce a console at lower cost without affecting the quality of reproduction.

It will be obvious to those skilled in the art that various changes may be made in this device without departing from the spirit of the invention and therefore the invention is not limited to what is shown in the drawing and described in the specification but only as indicated in the appended claims.

I claim:

1. An acoustical device of the class described including a cabinet having a generally vertical front wall, a sounding board in said cabinet tilted rearwardly at its upper portion, sound producing means arranged on one side of said sounding board, the axis of said sound producing means being generally normal to said sounding board, resonating tubes arranged on the opposite side of said sounding board, said resonating tubes being of varying sizes and arranged in a manner whereby the edges of said resonating tubes furthest from said sounding board lie in a substantially vertical plane, the longer resonating tubes being arranged relatively remote from the bottom of the board and the shorter tubes being arranged relatively remote from the top of the board, whereby a minimum of space is occupied by the sounding board and tube construction.

2. An acoustical device of the class described including a cabinet having a generally vertical front wall, a sounding board in said cabinet tilted rearwardly at its upper portion, sound producing means arranged on one side of the sounding board, the axis of said sound producing means being generally normal to said sounding board, a housing within said cabinet in spaced relation to said sound producing means

and cooperating with said sounding board to envelop said sound producing means, openings in said sounding board communicating with the space between said sound producing means and the housing therefor, and valve means cooperating with said openings.

3. The structure recited in claim 2, said valve means being manually adjustable.

4. An acoustical device of the class described including a cabinet having a generally vertical front wall, a sounding board in said cabinet tilted rearwardly at its upper portion, sound producing means arranged on one side of said sounding board, the axis of said sound producing means being generally normal to said sound producing means, resonating tubes arranged on the opposite side of said sounding board, said resonating tubes being of various sizes and arranged in a manner whereby the edges of the resonating tubes furthest from the sounding board lie in a substantially vertical plane, the longer resonating tubes being arranged relatively remote from the bottom of the board and the shorter tubes being arranged relatively remote from the top of the board, a housing in spaced relation to said sound producing means and cooperating with said sounding board to envelop said sound producing means, said sounding board being formed with openings communicating with the space between said sound producing means and the housing therefor, and valve means cooperating with said openings.

5. The structure recited in claim 4, said valve means being manually adjustable.

6. An acoustical device of the class described comprising a sounding board, sound producing means arranged on one side of said sounding board, the axis of said sound producing means being generally normal to the plane of said sounding board, resonating tubes arranged on the other side of said sounding board, generally tubular sound concentrating means partially enveloping said tubes, said concentrating means having an annular inturned portion, said concentrating means cooperating with said sounding board to effect a pleasant and intimate tonal quality.

7. An acoustical device of the class described comprising an inclined sounding board, sound producing means arranged on one side of said sounding board and generally normal to its plane, resonating tubes arranged on the other side of the sounding board and also generally normal to its plane, sound concentrating means partially substantially cylindrical and partially annularly converging, said sound concentrating means partially enveloping said tubes and cooperating with said sounding board to effect a pleasant and intimate tonal quality.

8. An acoustical device of the class described comprising an inclined sounding board, a sound producing means arranged in operative relation to said sounding board, resonating tubes arranged on said sounding board, said tubes and said sound producing means having generally parallel axes, said resonating tubes being of various sizes and arranged in a manner whereby the edges of said resonating tubes furthest from said sounding board lie in a substantially vertical plane, said inclined sounding board extending rearwardly at its upper portion, whereby a minimum of space is occupied.
